DESIGN FOR A CLOSURE

John E. Sharp, New Kensington, Pa., assignor to
Aluminum Company of America, Pittsburgh,
Pa., a corporation of Pennsylvania

Application October 15, 1943, Serial No. 111,375

Term of patent 14 years

(Cl. D58—26)

To all whom it may concern:

Be it known that I, John E. Sharp, a citizen of the United States, residing in New Kensington, in the county of Westmoreland and State of Pennsylvania, have invented a new, original, and ornamental Design for Closures, of which the following is a specification, reference being had to the accompanying drawing forming part thereof.

Fig. 1 is a top plan view of a closure showing my new design.

Fig. 2 is a side elevational view of said closure; and

Fig. 3 is a side elevational view of said closure taken at a different point than that of Fig. 2.

I claim:

The ornamental design for a closure, as shown.

JOHN E. SHARP.
